UNITED STATES PATENT OFFICE.

NATHAN KASDAN, OF BRONX, AND DANIEL POLLACK, OF BROOKLYN, NEW YORK, AS-SIGNORS TO MAJESTIC MACHINE & TOOL CO., INC., OF NEW YORK, N. Y., A CORPORATION OF NEW YORK.

VANITY BOX.

Application filed April 26, 1923. Serial No. 634,715.

The invention relates to improvements in vanity boxes or cases of the class containing a mirror and adapted to receive a face-powder compact and a rouge compact and puffs or pads therefor.

One object of our invention is to provide a vanity case of the class referred to which shall be very durable and have its parts so constructed and connected together that whether the case is opened or closed said parts will be devoid of looseness and especially devoid of pivoted links and the like.

Our box or case comprises a bottom or body member, a cover member hinged thereto and an intermediate slidable section connected by integral inflexible legs with a disk-plate or frame mounted in said body member, said intermediate section being normally housed within the top of said body member and adapted to be slid outwardly along the upper edge of said member and remain parallel therewith and have a firm bearing thereon, said intermediate section when supported on the rim of the body member being incapable of tilting downwardly at its forward portion projecting beyond the body-member. The disk-plate or frame secured in the body member of the case not only receives and guides the aforesaid legs during the sliding motion of the intermediate section or member of the case or box but also furnishes a compartment for a rouge compact and its puff or pad, which compartment is normally concealed by said intermediate section or member.

The cover-member may be utilized to receive a face-powder compact and a puff or pad therefor, and the intermediate slidable section or member may carry the mirror, or said cover-member may be provided with the mirror and said intermediate slidable section or member utilized to hold the face-powder and the puff or pad therefor, as may be preferred, in either case the intermediate section serving when in its initial position to expose the face-powder and conceal the rouge and when slid outwardly to expose the rouge for use.

The invention will be fully understood

from the detailed description hereinafter presented, reference being had to the accompanying drawings, in which:

Fig. 1 is a perspective view of the vanity box or case shown closed;

Fig. 2 is a perspective view of the same illustrating the box as having been opened to expose the mirror and compartment for the face powder;

Fig. 3 is a like view of the same illustrating the box as having been manipulated to expose the compartment for face powder, the compartment for rouge and the mirror;

Fig. 4 is a central vertical longitudinal section, partly broken away, of the box with its parts shown in the position in which they are illustrated in Fig. 3;

Fig. 5 is a like section of the box shown closed;

Fig. 6 is a vertical transverse section through a portion of the same taken on the dotted line 6—6 of Fig. 4;

Fig. 7 is a top plan view, partly in section and partly broken away, of the box or case in open position, the slidable middle member shown at the right hand side of Fig. 4 being omitted and the sectional portion of Fig. 7 being horizontally through the legs connected with said member;

Fig. 8 is a vertical section through a portion of the case taken on the dotted line 8—8 of Fig. 7;

Fig. 9 is a plan view of a modified construction of a vanity box or case, shown in full open position, embodying our invention, the middle or intermediate slidable section shown at the right hand side of Fig. 4 as carrying the mirror being in the construction presented in Fig. 9 utilized as the compartment for the face-powder, while the mirror is located within the top of the box in lieu of the face-powder compartment being formed in the top member of the box as in the form of the invention shown in Figs. 1 to 8 inclusive;

Fig. 10 is a vertical section through the box or case presented in Fig. 9, the section being on the dotted line 10—10 of Fig. 9;

Fig. 11 is a top plan view of a portion

of the box or case shown in Fig. 10, the middle or slidable member for the face-powder being omitted and the legs connected therewith being in section;

5 Fig. 12 is a vertical section, on a larger scale, taken on the dotted line 12-12 of Fig. 10, and

Fig. 13 is a perspective view of the lipstick holder detached from the box or case.

10 In the drawings, referring to Figs. 1 to 8 inclusive, showing one form of our invention, 20 denotes the bottom or body member of the box or case, 21 the cover member thereof, and 22 an intermediate slidable member carrying therein a mirror 23. The members 20, 21 and 22 are circular in outline, as shown, and when in closed position take the relation to one another shown in Figs. 1 and 5. The members 20, 21 are connected together by a hinge 24 which permits the member 21 to be closed upon the body member 20 or turned from over the same.

15 The body-member 20 is formed with an annular vertical rim 25 which, near its upper edge, is offset inwardly to form an outer annular shoulder 26 on which the edge of the skirt 27 of the cover-member 21 may seat when the box is closed and an inner annular shoulder 28 which we utilize as means for retaining within the body member 20, a disk plate or frame 29 which we press below said shoulder 28 and which has upwardly extending yielding segmental sections 30 which snap below said shoulder 28 and cooperate therewith in securely positioning the plate or frame 29 with the body or bottom member 20 of the box.

20 The plate or frame 29 has eccentrically thereof and as near as may be convenient to the hinge 24, a downwardly extending circular flange 31 whose lower edge engages the bottom of the box, as shown in Figs. 4 and 5. The flange 31 in cooperation with the bottom of the box forms a compartment 32 for a rouge compact 33 and a puff or pad 34 therefor. We preferably vertically slit the flange 31 at a few points to form spring fingers 35 (Fig. 7) which are pressed slightly inwardly and serve as means for gripping the base of the compact 33 and holding the compact in stationary position. Around the upper edge of the compartment 32 the metal of the plate 29 and flange 31 is formed into an upwardly projecting annular bead 36, which serves to stiffen the plate 29 and deepen the compartment 32 and also as a rest and support for the intermediate slid- 35 able section 22 of the box when the box is opened to the extent shown in Fig. 2 and also when the box is entirely closed, as shown in Fig. 5.

25 The plate or frame 29 is below the upper edge of the body-member 20, and above said plate or frame and within the upper end of said body-member is formed a chamber

which normally receives and confines the slidable member 22, which is a disk-plate having an edge rim which secures the mirror 23, as shown.

30 The plate or frame 29 is formed with two straight parallel slots 37, one being at each side of the compact chamber 32, and these slots receive and guide flat legs 38 which are slit and bent downwardly from the metal of the bottom of the slidable member 22 near the inner edge thereof. The lower ends of the legs 38 are bent laterally below the plate 29, as at 39, and prevent the separation of the member 22 from the plate 29, and said legs are of such length that when the member 22 is slid outwardly on the upper edge of the body-member 20 the bent-ends 39 thereof will engage the bottom of the plate 29 and firmly hold the member 22 on said edge of the body-member and parallel therewith, as shown in Figs. 4 and 6, thereby preventing the outer portion of said member 22 which projects beyond the member 20 from tilting downwardly, this result being very desirable. When the slidable member 22 is slid inwardly along the upper edge of the body-member 20, said member 22 will finally become concentric with the member 20 and settle down into the upper end thereof and seat upon the beading 36 of the plate 29, the legs 38 then descending through the slots 37. The mirror 23 and member 22 will remain within the body-member 20, in the position shown in Fig. 2, except when it is desired to expose the rouge compartment 32, and when the use of the rouge is required, the lip 40 at the outer edge of the mirror will be taken hold of as a thumb-hold and the edge of the member 22 thereat lifted from the body-member 20 and said member 22 will thereupon be slid outwardly along the upper edge of said member 20 to the position shown in Figs. 3 and 4. When the use of the rouge has ceased, the member 22 will be slid back to its initial position within the body-member 20.

35 The cover-member 21 of the box provides within it a compartment for a face-powder compact 41 and a puff or pad 42 for use therewith and said compartment becomes exposed by the mere opening of said cover-member, the mirror 23 then being in convenient position for use, as shown in Fig. 2.

40 The box or case of our invention thus comprises a body or bottom member, a cover member hinged thereto and an intermediate slidable member, said slidable member being devoid of pivoted links and the like and adapted to firmly rest upon the upper edge of the member which normally houses it and from which it is slid. In the form of the invention shown in Figs. 1 to 8 inclusive, the slidable member 22 carries a mirror, the face-powder compact is within the cover-member 21 and the rouge in the bottom member 20.

We find it entirely convenient however to so fashion and connect the parts of our vanity box or case, that the cover member shall carry the mirror and that the intermediate slidable section shall carry the face-powder, and a construction with the parts thus arranged is shown in Figs. 9 to 11 inclusive.

Referring to Figs. 9 to 11 inclusive, 43 denotes the bottom member of the box, 44 the cover-member hinged, at 45, thereto and 46 the intermediate slidale member which is of cup-shape and provides a compartment for a face-powder compact 47 and powder-puff or pad 48. The cover 44 has a mirror 49 secured within it. The body-member has a rim 50 off-set inwardly in its upper portion to form an outer annular shoulder 51 to serve as a seat for the skirt of the cover 44 and an inner annular shoulder 52 to hold down a disk plate or frame 53 which performs the duties hereinbefore described of the disk-plate or frame 29 of Fig. 4. The plate or frame 53 is flanged downwardly at 54 to form a compartment 55 for a rouge-compact 56 and its puff or pad 57, the compartment 55 corresponding with the compartment 32 of Figs. 4 and 5. The disk plate or frame 53 has parallel slots 58 to receive and guide the legs 59 slit and bent downwardly from the bottom of the slidale member 46 and the lower ends of which legs are bent laterally, as at 60, to prevent the separation of the member 46 from the plate or frame 53. The slots 58 and legs 59 correspond with the slots 37 and legs 38 of Figs. 6 and 7, and the slidale member 46 has the same operation as the slidale member 22 of Fig. 4 but in this instance carries a powder compact instead of a mirror.

When the cover-member 44 is opened the mirror 49 and face-powder compartment are exposed, and when it is desired to use the rouge the outer edge of the slidale member 46 is lifted from the body-member 43 and said member 46 is then slid outwardly upon the upper edge of the rim 50 of said member 43, the rouge, face-powder and mirror then all being exposed.

The details of the case shown in Figs. 9 to 12 inclusive will be understood without further specific description in view of the description hereinbefore given with respect to Figs. 1 to 8 inclusive.

In the construction shown in Figs. 9 to 11 inclusive, we form an opening 61 in the body rim 50 at the front of the box to admit a lip-stick holder 62, and we slit and turn downwardly from the plate 53 oppositely disposed lips 63 to engage, guide and position said holder 62, as will be understood on reference to Figs. 11 and 12. The bottom of the box is slotted, as at 64, to receive the stem of the button 65 of the usual slide within the holder 62. With the addition of the

lip-stick holder, the vanity case seems to be as complete as ordinary requirements would render necessary.

What we claim as our invention and desire to secure by Letters Patent, is:

1. A vanity case or box comprising a body-portion having a bottom and rim, a cover having a skirt hinged to the rim of said body-portion, a disk-frame fitted within said body-portion and having a walled opening forming a chamber to receive a rouge compact and its pad, a slidale intermediate section adapted to seat within the upper part of said body-portion above said disk frame, and means connecting said intermediate section with said disk frame and permitting the same to be slid therefrom along and parallel with the upper edge of said rim comprising legs rigid with the underside of said section and parallel guide slots in said disk-frame down through which said legs are inserted, the lower ends of said legs being bent laterally to prevent the separation of said section from said disk-frame, said walled opening being formed by an annular flange integral with and surrounding an opening in said disk-frame and extending downwardly to the bottom of said body-portion, and an annular upwardly projecting beading being formed around the upper edge of said opening to form a seat for said intermediate section when said section is in its initial position closing the chamber for the rouge compact.

2. A vanity case or box comprising a body-portion having a bottom and rim, a cover having a skirt hinged to the rim of said body-portion, a disk-frame fitted within said body-portion and having a walled opening forming a chamber to receive a rouge compact and its pad, a slidale intermediate section adapted to seat within the upper part of said body-portion above said disk-frame, and means connecting said intermediate section with said disk-frame and permitting the same to be slid therefrom along and parallel with the upper edge of said rim comprising legs rigid with the underside of said section and parallel guide slots in said disk-frame down through which said legs are inserted, the lower ends of said legs being bent laterally to prevent the separation of said section from said disk-frame, said body-portion having an opening at its front in said rim to admit a lip-stick holder and said disk-frame having opposite lips bent downwardly therefrom to embrace and guide said lip-stick holder, the bottom of said body-portion being slotted at said opening to permit the button on the holder to slide below the same.

3. A vanity case or box comprising a body-portion having a bottom and rim, a cover having a skirt hinged to the rim of said body-portion, a disk-frame fitted within said body-portion and having a walled opening

- forming a chamber to receive a rouge compact and its pad, a slidable intermediate section adapted to seat within the upper part of said body-portion above said disk-frame, and
- 5 means connecting said intermediate section with said disk-frame and permitting the same to be slid therefrom along and parallel with the upper edge of said rim comprising legs rigid with the underside of said section
- 10 and parallel guide slots in said disk-frame down through which said legs are inserted, the lower ends of said legs being bent laterally to prevent the separation of said section from said disk-frame, said intermediate section having a mirror secured therein, and
- 15 said cover having therein a face-powder compact and pad therefor.
4. A vanity case or box comprising a body-portion having a bottom and rim, a
- 20 cover having a skirt hinged to the rim of said body-portion, a disk-frame fitted within said body-portion and having a walled opening forming a chamber to receive a rouge compact and its pad, a slidable intermediate
- 25 section adapted to seat within the upper part

of said body-portion above said disk-frame, and means connecting said intermediate section with said disk-frame and permitting the same to be slid therefrom along and parallel with the upper edge of said rim comprising legs rigid with the underside of said section and parallel guide slots in said disk-frame down through which said legs are inserted, the lower ends of said legs being bent laterally to prevent the separation of said section from said disk-frame, said walled opening being formed by an annular flange integral with and surrounding an opening in said disk-frame and extending downwardly to the bottom of said body-portion, and said flange being slit vertically to form fingers which are pressed inwardly and serve to grip the base of the compact applied within said opening.

Signed at New York city, in the county 45
and State of New York, this 25th day of
April, 1923.

NATHAN KASDAN.
DANIEL POLLACK.
